UNITED STATES PATENT OFFICE.

BENJAMIN F. SMITH, OF BAY CITY, MICHIGAN.

COMBINED TELEPHONE AND PUSH-BUTTON.

SPECIFICATION forming part of Letters Patent No. 635,944, dated October 31, 1899.

Application filed November 26, 1897. Serial No. 659,822. (No model.)

To all whom it may concern:

Be it known that I, BENJAMIN F. SMITH, a citizen of the United States, residing at Bay City, in the county of Bay and State of Michigan, have invented a new and useful Combined Telephone and Push-Button, of which the following is a specification.

My invention pertains to improvements in electric call-bell and telephone service especially adapted for residences, hotels, or other buildings; and the objects of my invention are, first, to provide a simple and effective system combining in one instrument the features of a push-button to effect the call and a telephone for communication, the device being applicable to the present systems of wiring commonly employed for call-bells and similar service, and, second, to provide a combined telephone and push-button adapted to be placed in circuit with a battery and an electric bell or annunciator so constructed that the circuit is normally broken at the telephone except when the telephone is being used, thus drawing on the battery only during actual use of the instrument. I attain these objects by the devices illustrated in the accompanying drawings, in which—

Figure 1 is a vertical section of the combined telephone and push-button to an enlarged scale. Fig. 2 is a plan of circuit such as is commonly used for call-bells in residences, showing the application of my invention thereto.

In both views similar letters and figures of reference refer to similar parts.

As is well known, the simple call-bell system now in common use consists of a push-button or other contact-making device permanently attached to the wall of the room, as at *a* in Fig. 2. From the button wires *b* and *b'* are run through a battery *c* and call-bell *d*, located in any desired part of the house. In order to utilize this system of wiring for the purpose of telephonic communication as well as for the present call-bell service, I apply in place of the ordinary push-button a combined telephone and push-button of construction and operation such as to adapt itself particularly to this use.

The combined telephone and push-button

is preferably constructed as shown in detail in Fig. 1. An outer casing 1 of any suitable form allowing access to the interior has two contact-points 2 and 2^a on its base, connected with the wires *b* and *b'*. A contact-piece 3, 55 attached to the stem of the push-button when the latter is pressed down, completes the circuit through the contact-points. The push-button is returned to its normally-raised position by two conducting-springs 4 and 4^a, 60 connected at their lower ends to the contact-points 2 and 2^a and at their upper ends to an insulating-arm 5, fixed to the stem of the push-button. A telephone-diaphragm having an opening at its center, through which the 65 stem 6 passes, is provided at the outer end of the casing 1. A telephone-core 7 and its coil 8 are supported by the base of the casing in proper relation to the diaphragm, as in an ordinary telephone. Two oppositely-placed 70 springs 9 and 9^a are attached to the bottom of the telephone-coil and are electrically connected to the ends of the coil, their lower ends when the push-button is raised being normally in electrical contact with the two 75 springs 4 and 4^a before mentioned, this contact being effected through the screws or pins 10, by which the lower springs are attached to the insulating-piece 5. A cam or distance-piece 11, of insulating material, is adapted to 80 make or break the electrical contact between the springs 4^a and 9^a by being slightly rotated by a lever 12 and a spring-retained push-button 13. The cam in its normal position when the push-button is out presses the springs 85 apart and breaks the circuit between the telephone and the line.

The operation of the combined telephone and push-button is as follows: By pressing the button and bringing the contact-piece 3 90 against the two points 2 and 2^a a circuit is completed between the battery *c* and call-bell *d*, ringing the bell. Releasing the push-button breaks the circuit and pressing the side button 13 turns the cam 11 sufficiently to complete electrical communication through the pin 10 between the spring 9^a and the push-button spring 4^a, thus throwing the telephone-coil into circuit. A receiver *e*, which may be of the ordinary Bell type, attached in shunt 95 100

with the bell *d*, will then be in electrical communication with the instrument *a* and conversation may be carried on over the line. Upon releasing the spring-pressed side button 13 the cam rises and breaks the circuit.

5 By means of the device herein shown and described I produce a simple, compact, and efficient combined telephone and push-button that can be readily applied to existing 10 systems of call-bell wiring.

A feature of the operation of this device is 15 that the full battery-current is only used while the call-bell is being rung. The circuit is then broken until the side button is pressed and the telephone-circuit established. While 20 the telephone is in use, the battery serves to increase the magnetic effect of the cores, and consequently to increase the sensitiveness of the telephone.

25 As shown in the drawings, the stem of the push-button passes through a hole in the center of the diaphragm. It is found in practice with this instrument that this construction increases the sensitiveness of the diaphragm, and consequently the transmitting power and the receiving power of the telephone.

The high resistance of the fine telephone-coil prevents any considerable drain on the battery and prolongs its life.

30 Although the form of casing shown herein is especially adapted for attachment to the wall in the same manner as an ordinary push-button, yet the spirit of my invention would still be preserved if the instrument were connected with the main wires by flexible wires 35 or other suitable means, thus admitting of

its convenient use by persons of different stature.

What I claim as my invention, and desire to secure by Letters Patent, is—

1. In combination with a telephone structure, a push-button included therewith and forming a part thereof; the stem of the push-button passing through the core and diaphragm of the telephone, together with a cam or equivalent means for holding the circuit normally broken, and a push-button connected therewith for completing the circuit while the telephone is in use, all substantially as described and for the purpose set forth.

2. The combination with a telephone structure of a push-button forming a part thereof, the stem of the push-button passing through the core and diaphragm of the telephone; flexible conducting-springs attached to the push-button terminals for raising the push-button and also to complete the telephone-circuit, a contact-piece attached to the stem of the push-button for completing the call-bell circuit; flexible conducting-springs attached to the terminals of the telephone-coil for completing the telephone-circuit; and a spring-operated cam for raising the conducting-spring and holding the telephone-circuit normally broken, substantially as and for the purpose described.

In testimony whereof I sign this specification in the presence of two witnesses.

BENJAMIN F. SMITH.
